HENRY W. WINTER, OF METHUEN, MASSACHUSETTS, ASSIGNOR TO UNITED SHOE MACHINERY COMPANY, OF PATERSON, NEW JERSEY, A CORPORATION OF NEW JERSEY.

STAMPING-MACHINE.

1,149,240.

Specification of Letters Patent. Patented Aug. 10, 1915.

Application filed December 27, 1910. Serial No. 599,495.

To all whom it may concern:

Be it known that I, HENRY W. WINTER, a citizen of the United States, residing at Methuen, in the county of Essex and State of Massachusetts, have invented certain Improvements in Stamping-Machines, of which the following description, in connection with the accompanying drawings, is a specification, like reference characters on the drawings indicating like parts in the several figures.

This invention relates to machines for stamping, embossing or burning a trade mark or inscription upon sheet material, especially on portions of boots or shoes.

An object of the invention is to improve the construction and organization of stamping machines as heretofore constructed, to increase the speed of their operation by rendering them automatic in action, to improve their accuracy and to adapt them for certain operations which it has not been possible to effect satisfactorily by machines of this class as formerly constructed.

In stamping leather differing in quality and grade it is necessary to vary the length of time during which the type or die remains in engagement with the work. For example, in burning a trade mark upon coarse, dark colored leather the time required to produce a perfect mark will be much longer than the time required to produce the same mark on a fine, light colored leather. It is also desirable to vary the

length of the impression according to the size of the mark or inscription to be made, a trade mark covering a large area requiring more time than a mark indicating size or case number, for example. The machine herein disclosed comprises a work support or platen, a stamping head and mechanism for causing relative movement of the support and head to impress work placed between them.

An important feature of the invention consists in the provision of means for controlling the length of the impression, said means acting automatically at the expiration of a predetermined period to effect the separation of the support and stamping head. In a preferred embodiment of the machine the stamping head is moved toward the

work, by a rotatable actuator, such as a cam or eccentric acting through suitable connecting mechanism and is brought to rest upon 55 engaging the work. After the required interval, which may be preliminarily determined by the operator, the actuator is restarted and the stamping head retracted. In the machine herein disclosed the actuator 60 is rotated from the main shaft of the machine, being disengaged from its driving mechanism and brought to rest when the stamping head is in its lowest position by the operation of a clutch dog. A controlling 65 device is arranged to be driven from the main shaft, and, after an interval which depends upon the initial setting of the controlling device by the operator, the dog is retracted and the actuator restarted. The 70 controlling device is thereupon automatically disconnected and returned to initial position where it may be adjusted if desired to vary the length of the next impression. As herein shown, the stamping 75 head and controlling device are actuated from the main shaft by separate trains of mechanism and this arrangement constitutes an important feature of the invention. In addition to lending itself particularly well 80 to the requirements of the machine from a mechanical standpoint, this construction permits the operation of the controlling device and the stamping head in an accurate and independent manner and at speeds best suited 85 to their different character.

Another feature of the invention relates to a novel construction and arrangement of the stamping head whereby the type or die may be heated for burning a mark into the 90 work or for applying gold leaf thereto. To this end the stamping head is provided with a type or die holder having an enlarged transversely extending portion bored to receive electrical heating coils and in close 95 proximity to the heating coils is disposed means for retaining the type or die, preferably arranged to permit the type or die to be readily inserted or removed therefrom. The holder is adjustably mounted in the stamping head in order that the point of nearest approach to the support or platen may be varied in changing from thin to thick work 100 or vice versa, and it is yieldingly maintained

in position to allow for slight variations in the thickness of the work and to prevent an excessive degree of pressure.

The construction whereby a yielding action of the die holder is secured constitutes another important feature of the invention inasmuch as it is essential to regulate to a nicety the degree of pressure exerted by the heated die upon the work. In the embodiment of the invention herein shown a compression spring is interposed between a thrust piece adjustably mounted in the stamping head and a shoulder on the stem of a die-carrying member. The thrust piece is perforated to receive the stem of the die-carrying member and the stem is provided with an adjustable stop so that the compression of the spring and also the position of the die may be adjusted, both adjustments being effected independently.

Still another feature of the invention relates to the work support or platen and gages for locating the work properly thereon. In order to permit access to the interior 25 of the machine and the gage adjusting mechanism a removable bed plate is provided and the platen and gages are mounted upon this plate. A slide carrying sockets is movably mounted in ways on the bed plate 30 and gage pins project from said sockets through the platen, being yieldingly supported in said sockets in order that they may move out of the path of the stamping head during the impression.

35 The features above enumerated and others incident to the invention will be best understood and appreciated from the following description of a preferred embodiment selected for purposes of illustration in connection with the accompanying drawings, in which:—

Figure 1 is a view in perspective. Fig. 2 is a sectional side elevation. Fig. 3 is a rear elevation partly in section. Fig. 4 is a view 45 in perspective of the removable bed plate and gage mechanism. Fig. 5 is a view in perspective of the controlling shaft.

The main shaft 2 of the machine, which is journaled in the frame or casing 4, carries 50 on one end a driving pulley 6, by which the machine may be actuated from any suitable source of power. Within the casing there are keyed or otherwise rigidly secured to the shaft 2 a pinion 8 and a worm wheel 10. 55 The pinion 8 meshes with a gear 12 journaled upon a stationary transverse spindle 14. The gear 12 constitutes the driving member of a clutch and is provided on one side with an elongated hub and on the other 60 is recessed to receive one end of a loose clutch member 16 having a cam or eccentric 17 formed integral therewith. A clutch controlling ring 18 is fitted upon the member 16 and is provided with pockets for rollers, as 65 in the well known type of Horton clutch.

When the clutch is disengaged the rollers lie in depressions formed in the member 16, one being shown in Fig. 3, but when moved out of such depressions by a slight rotary movement of the ring 18 the rollers become 70 wedged between the loose clutch member 16 and a hardened bushing 20 fast to the driving gear 12 of the clutch so that the eccentric 17 will be rotated by the gear 12. A spring 22 lying in a circumferentially extending slot in the controlling ring 18 tends to rotate the ring relatively to the loose member 16 for causing the clutch to engage. Reverse rotation of the loose member 16, due to the action of the spring 22, is prevented by the frictional engagement of a stationary arm 15 with a fiber disk 13 pinned to the loose member 16. Forward rotation of the ring 18 is prevented by one of two dogs 24, 26, mounted to turn about 80 the transverse spindle 28 as an axis and arranged to engage teeth 30, 32, respectively on the periphery of the ring 18. Rotation of the eccentric 17 and movement of the stamping head, relatively to the platen, as will 90 hereinafter appear, is controlled by moving the dogs 24, 26 to engage or disengage the teeth on the ring 18.

The stamping head of the machine comprises a tubular slide or carrier 40 having 95 parallel oppositely disposed ribs fitted to slide in vertical guideways formed partly in the frame and partly by face plates 42 secured to the frame. The die or type holder 46 has a tapered shank 47 which is 100 removably received in a tapered socket formed in the lower end of an adjustable socket piece or stem 48 in the carrier 40. The die holder is yieldingly maintained in position by a stiff spiral spring 50 bearing 105 at its lower end against a shoulder formed on the socket piece or stem 48 and at its upper end against the thrust piece 52 threaded into the upper end of the tubular carrier 40. The compression of the spring 50 may be adjusted by turning the thrust piece 52 into or out of the carrier 40. The 110 socket piece or stem 48 is grooved at its rear side and is prevented from turning by a screw 43, the end of which projects through the carrier 40 and into the groove. The carrier is split or slotted at its upper end and may be contracted to clamp and maintain the thrust piece in any adjusted position by means of a binding screw 51 extending between ears formed on the carrier at either side of the slot. The thrust piece 52 is drilled to receive the upper reduced end of the socket piece or stem 48 which extends out through the thrust piece and is threaded to receive a pair of nuts which act as an adjustable stop to prevent the spring 50 from forcing the plunger downwardly out of the carrier 40.

Projecting from the rear side of the car- 130

rier 40 are a pair of lugs 44 which form a short guideway for a transverse block 45 pivotally connected to the forward end of a lever 47 which is oscillated by the eccentric 17 acting through an eccentric rod 49. The oscillation of the lever 47 imparts vertical reciprocatory movement to the carrier 40 to effect the stamping or marking operation and then to retract the carrier.

10 The die holder 46 extends transversely of the carrier 40 and is bored out to receive a sleeve of insulating material and a pair of resistance coils 54 whereby the die or type may be electrically heated. On its 15 lower face and adjacent to the heating device the holder 46 is provided with a fixed undercut rib 55 with which coöperates a movable undercut slide 56 normally pressed toward the rib 55 by a spring 57. The slide 20 56 may be retracted to permit the insertion or removal of the type or die by a lever 59 pivoted to a lug at the rear of the holder and having an angularly extending toe or projection engaging a portion of the slide 56.

25 The platen 60 is attached to a removable bed plate 62 having a beveled rear edge adapted to fit into an undercut slot formed in the casing, the plate being secured in place at its front end by suitable screws. A 30 pair of adjustable gage pins 64 project upwardly through the platen 60 and serve to locate the edge of the work with relation to the stamping head, while an adjustable gage 66, mounted in a perforated lug 67 at the 35 rear side of the bed plate 62, serves to determine the position of the end of the work. One desirable manner of arranging the gage pins 64 is illustrated in Fig. 4 in which 68 indicates a pair of undercut ways between 40 which is slidably mounted a plate 69 having sockets 70 for the gage pins 64 and a threaded ear for an adjusting screw 71. The adjusting screw is provided with collars for engaging a fixed part of the casing so that 45 rotation of the screw will move the plate 69 and the gage pins forwardly or rearwardly. The pins 64 are yieldingly mounted in the sockets 70, as shown in Fig. 2, in order that they may be depressed flush with 50 the surface of the platen when engaged by the slide 56 on the downward movement of the stamping head. The gage 66 may be adjusted by loosening a set screw threaded into the lug 67 and clamped in any adjusted position by the said means.

55 Returning now to the mechanism for controlling the operation of the dogs 24, 26, and thereby the eccentric 17, it will be found that the dog 24 is effective for starting and finally stopping the eccentric while the dog 26, which acts on the tooth 32, effects the stopping of the eccentric when the stamping head is in contact with the work and permits starting after the predetermined period necessary for securing a perfect impression has elapsed.

60 The dog 24 is keyed or otherwise rigidly attached to the spindle 28 and is moved out of engagement with the tooth 30 on the controlling ring 18 when the spindle is turned by the depression of an arm 72 70 also keyed to the spindle. A suitable spring acts upon the arm 72 to lift it and maintain the dog 24 in operative position. The arm 72 is provided with a hardened bearing piece at its outer end which normally stands in the 75 path of a spring pressed latch piece 73 on a treadle actuated lever 74 pivoted to the front side of the casing. The lever 74 is normally elevated by a suitable spring, upward movement being limited by a stop 75 on the lever 80 which engages the casing at a point below the adjusting screw 71. When the lever 74 is depressed by the treadle rod the latch piece 73 swings the arm 72 downwardly, thus retracting the dog 24 and starting the 85 rotation of the eccentric 17. The latch piece 73 is pivotally mounted upon the lever 74 and normally pressed outwardly by a suitable spring. Outward movement of the latch piece is limited by a pin 76 projecting 90 from the lever 74 into an enlarged aperture in the latch. On the downward movement of the lever 74, after the arm 72 has been sufficiently depressed to retract the dog 24, the end of the latch piece 73 encounters a 95 fixed pin 77 projecting from the casing and thereby is moved to disengage the arm 72. Further downward movement of the treadle rod carries the latch piece 73 below the arm 72 and on the upward movement of the 100 treadle rod the latch piece is permitted to yield inwardly and pass the arm 72 without disturbing it. It will be seen that the mechanism above described insures a non-repeating 105 action of the machine.

110 The dog 26 normally rests on the periphery of the clutch ring 18, being maintained in position by a spring extending between a rearwardly projecting arm 79 on the dog and a stationary transverse pin 80. It will be understood that the teeth 30 and 115 32 on the clutch ring are displaced axially relatively to each other, the tooth 30 being in alignment with the dog 24, and the tooth 32, which is 180° behind the tooth 30, being located in alignment with the dog 26. When the tooth 30 is released by the dog 24 the clutch ring is permitted to rotate making half a revolution, and is then stopped by the engagement of the dog 26 with the tooth 32. 120 The eccentric 17 is rotated simultaneously with the clutch ring and is brought to rest with the latter when the stamping head engages the work. The dog 26 is permitted to remain in engagement with the tooth 32 125 holding the stamping head at rest for a predetermined interval and is then automatically retracted by any suitable mechanism, a preferred form of which will now be described.

Mounted for turning movement about the main shaft 2 is a bearing bracket 82 in which is journaled a shaft 83 having at its rear end a worm wheel 84 which meshes with the worm 10 on the main shaft. On its forward end the shaft 83 is provided with a worm 85 arranged to mesh with a worm wheel 86 on a transverse shaft 81. The bearing bracket 82 is supported at its forward end in such a way as to maintain the worm 85 in mesh with the worm wheel 86 by means of a hook shaped knock off piece 87 pivotally mounted on the transverse pin 80. On one end of the shaft 81, which will be termed hereinafter the controlling shaft, there is rigidly secured an arm 88 carrying a short pin which is arranged to engage the arm 79 of the dog 26 and swing the latter out of engagement with the tooth 32. The worm wheel 86 is provided with a pin 89 which is adapted to engage the knock off piece 87 and swing it rearwardly releasing the forward end of the bearing bracket 82 which thereupon drops carrying the worm 85 out of mesh with the worm wheel 86. Rigidly secured to the controlling shaft 81 is a sleeve 90 to which is connected a torsional spring 91 tending to rotate the shaft in the opposite direction from that in which it is moved by the worm 85. The spring 91 is free to reversely rotate the shaft 81 when the worm 85 is disengaged from the worm wheel 86. The reverse rotation thereof is limited by an adjustable stop 92 which projects from the hub of an apertured disk 93 and stands in the path of the pin 89, projecting on both sides of the worm wheel 86. The position of the stop arm 92 and consequently the initial position of the controlling shaft 81, may be adjusted by turning the disk 93. The latter is located on one side of the frame of the machine, as clearly shown in Fig. 1, and may be held in any adjusted position by a spring pressed locking pin 94, which is mounted in a casing secured to the frame adjacent to the disk.

It will be seen, that as the controlling shaft 81 is rotated by the worm 85 the arm 88 acts to retract the dog 26, and then the pin 89 acts upon the knock off piece 87 to release the bearing bracket 82. In order to swing the forward end of the bearing bracket upwardly carrying the worm 85 into mesh with the worm wheel 86 when the machine is started, there is provided on the spindle 28 a rearwardly projecting arm 95 arranged in the path of a lug, projecting from one side of the bearing bracket. It will be seen that as the spindle 28 is turned in starting the machine, the arm 95 will engage the lug upon the bearing bracket and lift the bracket into engagement with the knock off piece 87, the latter being permitted to swing rearwardly when displaced,

by a hook shaped portion on the bearing bracket and being drawn into engagement therewith by a suitable spring. The controlling shaft is therefore set in motion at the same time that the rotary actuator 17 for the die is clutched to the gear wheel 20 and the movement of the die initiated. This arrangement facilitates the operation of the controlling mechanism by giving it an appreciable interval to reach the point of restarting and so renders possible a very accurate timing of the machine particularly when an impression of brief duration is desired.

In operating the machine the work is placed upon the platen 60 with its edge against the gage pins 64, and its end against the gage rod 66, the gages having been previously adjusted in accordance with the position on the work at which the impression should appear. The treadle rod is then depressed disengaging the dog 24 from the tooth 30 and simultaneously swinging the worm 85 into mesh with the worm wheel 86. As soon as the dog 24 has been moved sufficiently to release the tooth, the spring 22 immediately turns the ring 18 so that the tooth is moved out of the path of the dog 24, and the latter bears against the back of the tooth when the spindle 28 returns to its initial position on being disengaged by the latch piece 73. The parts of the machine are shown in this position in Fig. 2. The movement of ring 18 sets the eccentric 17 in motion, and the stamping head is moved downwardly to engage the work. When this occurs the tooth 32 has moved into position to be engaged by the dog 26, and the eccentric 17 is therefore brought to rest with the die in engagement with the work. In the meantime the controlling shaft 81 is being rotated by the worm 85 from its initial position, which is determined by the position of the stop 92, and after the desired interval the arm 88 acts to retract the dog 26, thus permitting restarting of the eccentric and effecting upward movement of the stamping head. After the arm 88 has acted upon the dog 26, the pin 89 comes into engagement with the knock off piece 87, and releases the bearing bracket 82 which thereupon carries the worm 85 out of mesh with the worm wheel 86, and permits the torsional spring 91 to return the controlling shaft 81 to its initial position. When the eccentric has completed one revolution and returned the stamping head to its highest point the tooth 30 is again engaged by the dog 24 and the eccentric brought to rest.

The present machine is adapted for impressing different kinds of marks upon different classes of work. If it is desired to burn a trade mark into the work, a suitable die is inserted in the holder and heated to the proper temperature by means of the

heating coils 54, and the regulating disk 93 is set for an impression of the proper duration. In stamping a gold leaf mark upon the work, a thin sheet of gold leaf is placed over the work after the latter has been sized, and a heated die is pressed on the gold leaf causing the latter to adhere to the material where it has been engaged by the die. The interval required for a perfect impression may be determined by experiment, and the regulating disk 93 set accordingly. In the machine herein disclosed the length of the impression may be varied from an instantaneous impression to one lasting about 20 seconds.

Having thus described my invention what I claim as new and desire to secure by Letters Patent of the United States is:—

1. A machine of the class described having, in combination, a main shaft, a movable die operatively connected to the main shaft and arranged to be actuated thereby, and a controlling device for regulating the length of the impression of the die having separate driving connection with the main shaft and arranged to be set in motion simultaneously with the movement of the die.

2. A machine of the class described having, in combination, a main shaft, two separate trains of mechanism operated by the main shaft, a die actuated through one train of mechanism, and a controlling device for governing the movement of the die actuated through the other train of mechanism, and means for simultaneously setting in motion both trains of mechanism.

3. A machine of the class described having, in combination, a main shaft, two separate trains of mechanism operated by the main shaft, treadle actuated means for simultaneously setting in motion both trains of mechanism, a die actuated through one train of mechanism, a controlling device actuated through the other train, and means for interrupting effective communication through the latter train of mechanism when the controlling device acts.

4. A machine of the class described having, in combination, a driving shaft, a gear continuously and positively driven from said shaft, a die carrier arranged to be actuated from the gear and having a spring interposed between it and the driving shaft whereby it may be moved into yielding engagement with the work by the driving shaft, and an automatically acting controlling device operated independently of the gear for regulating the duration of the yielding engagement of the die and the work.

5. A machine of the class described having, in combination, a relatively movable stamping head and platen, a driving member and two separate trains of mechanism one of which effects relative movement of

the head and platen to impress the work, a controlling device for governing the length of the impression arranged to be actuated by the second train of mechanism, and a single device operative for establishing simultaneously effective communication through both trains of mechanism.

6. A machine of the class described having, in combination, a platen, an oppositely disposed stamping die, a main shaft, an eccentric having operative connections with the main shaft, mechanism actuated by said eccentric for relatively moving the platen and die to impress the work, controlling mechanism having independent connection with, and being operated by, the main shaft for regulating the length of the impression, and treadle actuated means having separate connections for simultaneously setting in operation the eccentric and the controlling mechanism.

7. A machine of the class described having, in combination, a stamping head, a platen, and mechanism for relatively moving said head and platen comprising an eccentric and lever, a clutch whereby said eccentric may be rendered operative or inoperative, a clutch controlling ring, a pair of dogs arranged to act on said ring to cause said clutch to disengage, means under the control of the operator for moving one of said dogs to permit said clutch to engage, said second dog acting thereafter to disengage said clutch, and means acting automatically after a predetermined interval to move said second dog permitting the clutch to engage again.

8. A machine of the class described having, in combination, a stamping head, a platen, means for relatively moving said head and platen to impress work placed therebetween, a driving shaft, and mechanism connected therewith for effecting such relative movement, a rotatable controlling device for determining the length of said impression, an oscillatory bracket carrying a shaft for connecting the controlling device with the driving shaft, and treadle operated means for starting relative approaching movement of said head and platen and also swinging said shaft into operative position for starting the operation of the controlling device.

9. A machine of the class described having, in combination, a stamping head and platen, a driving shaft and connections for moving one relatively to the other to impress the work, a controlling device for regulating the length of the impression, and a bodily movable shaft constituting an operating connection between the driving shaft and controlling device arranged to be moved out of operative connection with the latter at the conclusion of the impression.

10. A machine of the class described having, in combination, a stamping head and platen, a driving shaft and an actuator rotated thereby, mechanism constructed and arranged to cause relative approaching movement of said head and platen during the first part of the movement of said actuator, automatically acting means for terminating said approaching movement, a controlling device, a shaft driven by said driving shaft for operating said controlling device, and means for moving said shaft out of operative relation with said controlling device after the latter has acted to permit restarting of the actuator. 15
11. A machine of the class described having, in combination, a stamping head, an actuator therefor, a controlling device for said actuator, an oscillatory bracket carrying a shaft for operating said controlling device when the machine is started, means for automatically stopping said actuator without affecting said controlling device, said controlling device being constructed and arranged to permit restarting of the actuator after a predetermined interval of rest. 20
12. A machine of the class described, having, in combination, a stamping head, an actuator therefor, and controlling mechanism for the actuator comprising a dog for stopping said actuator, a rotatable member carrying a pin arranged to move said dog to permit restarting of said actuator when said member has rotated to a certain position, and a swinging bracket carrying a shaft for rotating said member. 25
13. A machine of the class described having, in combination, a stamping head, an actuator therefor, and controlling mechanism for the actuator comprising a dog for stopping said actuator, a rotatable member arranged to move said dog to permit restarting of said actuator after a predetermined interval of rest, and means for returning said rotatable member to initial position after the actuator has been restarted. 30
14. A machine of the class described having, in combination, a stamping head, an actuator therefor, and controlling mechanism for the actuator comprising a dog for stopping said actuator, a rotatable member for moving said dog to permit restarting of said actuator after a predetermined interval of rest, driving means for said rotatable member, a spring for returning said member to initial position, and means for disconnecting said driving means to permit said spring to act. 35
15. A machine of the class described having, in combination, a stamping head, an actuator therefor, and controlling mechanism for said actuator comprising a dog for stopping said actuator, a rotatable member for moving said dog to permit restarting of said actuator, mechanism constructed and arranged to move said head and platen during the first part of the movement of said actuator, automatically acting means for terminating said approaching movement, a controlling device, a shaft driven by said driving shaft for operating said controlling device, and means for moving said shaft out of operative relation with said controlling device after the latter has acted to permit restarting of the actuator. 40
- for moving said dog to permit restarting of the actuator, a spring for returning said rotatable member to initial position, and an adjustable stop for determining the initial position of said rotatable member. 45
16. A machine of the class described having, in combination, a support, a die, a main shaft having actuating connections for causing relative movement of the support and die, a clutch included in said connection, and automatically acting means for controlling the clutch having an independent actuating connection with the main shaft and being arranged to cause said die and support to be relatively separated after an impression of predetermined duration. 50
17. A machine of the class described having, in combination, a stamping head and platen, a continuously rotating shaft, a swinging shaft having a transverse axis and being geared to said first mentioned shaft and rotated thereby, transmission mechanism interposed between the first mentioned shaft and the stamping head, and a controlling device arranged to be actuated by said swinging shaft when the transmission mechanism is set in motion. 55
18. A machine of the class described having, in combination, a relatively movable stamping head and work support, a plate mounted for sliding movement below said work support, sockets carried thereby, and gage pins yieldingly mounted in said sockets, projecting above said support and simultaneously adjustable by the movement of the plate. 60
19. A machine of the class described having, in combination, a casing, a stamping head movably mounted therein, a removable plate secured to said casing in alignment with said head, a platen mounted on one side of said plate, an adjustable gage carrying member mounted on the other side thereof, and gages projecting through said platen. 65
20. A stamping machine having, in combination, a driving shaft, a driven member, a clutch for engaging said shaft and driven member, and automatic clutch controlling means comprising a dog disposed to effect disengagement of the clutch after a predetermined movement, retracting mechanism for said dog including a bodily movable shaft operated from said driving shaft, and a knock off piece automatically actuated from the main shaft to interrupt the connection between said shaft and said retracting mechanism for the dog by rendering inoperative said bodily movable shaft. 70
21. A machine of the class described having, in combination, a removable bed plate, a platen carried thereby, a stamping head mounted for reciprocation toward and from the platen, an adjustable slide mounted on

the lower side of the bed plate, and yielding gage pins carried by the slide, projecting through the platen and disposed in the path of the stamping head so as to be depressed by the stamping head during the stamping operation.

5 In testimony whereof I have signed my

name to this specification in the presence of two subscribing witnesses.
